HARRY RUBIN, OF OAKLAND, CALIFORNIA, ASSIGNOR OF FORTY-NINE ONE-HUNDREDTHS TO EDWARD SUGARMAN, OF SAN FRANCISCO, CALIFORNIA.

ROTARY PUMP.

1,250,021.

Specification of Letters Patent. Patented Dec. 11, 1917.

Application filed March 6, 1917. Serial No. 152,541.

To all whom it may concern:

Be it known that I, HARRY RUBIN, a subject of the Emperor of Russia, residing at Oakland, in the county of Alameda and State of California, have invented a new and useful Improvement in Rotary Pumps, of which the following is a specification.

This invention relates to rotary pumps of the type employing a rotor journaled eccentrically in a casing and carrying radial vanes slidable endwise in bearings on the rotor; and has for its object to simplify and improve the construction and operation of such devices.

In prior constructions with which I am familiar the vanes extend no farther inwardly than the center of the rotor which results in a comparatively short bearing for these members with consequent liability of breakage under excessive strains. In the present device the vanes are overlapped and are made as long as or longer than the diameter of the rotor, whereby a much longer bearing support is provided. Where more than two vanes are employed they are made to cross each other by cutting away a portion of each where they intersect. Also in such prior constructions springs are generally made use of to control the vanes, while in the present device the outer end of each has a pin fitting into a rotatable ring or guide in the casing, which pins in addition to controlling the position of the vanes, lend additional support to the outer ends of the same and overcome the vibrations usually present in extremely long or wide vanes.

One form which my invention may assume is exemplified in the following description and illustrated in the accompanying drawings, in which—

Fig. 1 shows a longitudinal, central, sectional view of a device embodying my invention.

Fig. 2 shows a central cross-sectional view of the same.

In the drawings, I have shown a casing 10 in the form of a cylinder having an intake pipe 11 and an outlet pipe 12. Journaled eccentrically in the casing, in novel and improved bearings presently to be described, is a rotor comprising a shaft 13, having a boss 14 within the casing made in two parts held together by bolts 15, the ends of said boss being countersunk in the end walls of the casing.

Extending diametrically through the boss are intersecting slots to receive overlapping vanes 16, the latter being in the form of flat plates extending entirely through the slots and of a width sufficient to fill the axial length of the casing. One end of each vane carries pins 17 to enter rings 18, the latter rotatable in grooves formed in the end walls of the casing at the annulus thereof. The overlapping vanes are placed in contact with each other and receive support throughout the entire diameter of the boss and are freely slidable endwise therein and may be made as long or even longer than the diameter of the said boss. In the present form the proportion is such that when the vane is projected farthest from the boss the inner end thereof terminates near the periphery thereof at the opposite side.

Where more than two vanes are employed they can be crossed by cutting away a portion 19, as shown in Fig. 1. In such cases the pins 17 will have to move relative to the rings 18, and, therefore, I provide elongated slots 20 in the latter to receive the pins. It is obvious that the rings may be dispensed with and the pins 17 fitted in channel grooves in the casing. The rings not only serve to guide and control the vanes in an endwise direction, to insure a satisfactory fit between the casing and vane, but also support the said vanes against vibration at the outer ends so that longer and wider vanes may be used and the efficiency of the pump correspondingly increased. With the present construction I find it possible to increase the length and width of the vanes and the speed of the rotor to any desired extent without danger of excessive friction or breakage. By separating the two parts of the boss the notched vanes can be inserted or removed readily.

This pump is designed to rotate at high speeds, and therefore I provide a special form of journal bearing which will retain oil and insure constant lubrication. This comprises a sleeve 21 formed on each end wall of the casing and made somewhat larger than the shaft 13, and having a flange 22 at its inner end against which the boss 14 rests at the inner side, the outer side of said flange receiving a packing 23. A collar 24 is fitted within the sleeve 21 and forms an oil pocket around the shaft. This collar is pressed endwise against the packing 23, by means

of a flange member 26 clamped to the outer end of the sleeve 21; a packing 27, similar to the packing 23, being fitted between the member 26 and the adjacent end of the collar.

5 Oil is introduced to the bearing through a cup 28 carried on the sleeve and the end pressure against the packings 23 and 27 so expands them as to prevent leakage of oil from the pocket 25. With such a bearing an 10 exceedingly small quantity of oil is required to insure constant lubrication.

Various changes in the construction and arrangement of the several parts herein shown and described may be employed without departing from the spirit of my invention as disclosed in the appended claims.

Having thus described my invention, what I claim and desire to secure by Letters Patent is—

20 1. In a rotary pump, a casing having annular grooves in its opposing side walls, a rotor journaled eccentrically in the casing, vanes carried slidably in the rotor each having oppositely extending pins engaging in the annular grooves of the casing to retain one end adjacent the rim of said casing, and means operable in the casing grooves and connecting the pins of the vanes.

25 2. In a rotary pump, a casing having annular grooves in its opposing side walls, a rotor journaled eccentrically in the casing, vanes carried slidably in the rotor each having oppositely extending pins engaging in the annular grooves of the casing to retain

one end adjacent the rim of said casing, and 35 rings connecting the pins of the vanes and operating in the grooves of the casing.

3. In a rotary pump, a casing having annular grooves in its opposing side walls, a rotor journaled eccentrically in the casing, 40 vanes carried slidably in the rotor each having oppositely extending pins engaging in the annular grooves of the casing to retain one end adjacent the rim of said casing, and rings slidable around in the grooves of the 45 casing and formed with slots receiving the pins of the vanes.

4. In a rotary pump, a casing; a rotor journaled therein eccentrically, angularly related vanes, slidably carried by the rotor, 50 means to retain one end of each vane adjacent the rim of the casing, and means connecting the specified ends of the vanes for limited circumferential relative movement.

5. A rotary pump comprising a casing, 55 a rotor journaled eccentrically therein, vanes carried slidably in the rotor each having one end retained adjacent to the rim of the casing and the other end passed through the rotor and receiving support throughout the 60 entire diameter thereof, means on the casing for supporting and guiding the upper ends of the vanes, said means comprising a ring rotatable on the casing, and a connection between said ring and vane. 65

In testimony whereof I have hereunto set my hand.

HARRY RUBIN.
